UNITED STATES PATENT OFFICE.

WILLIAM B. LONG AND NATHAN E. HANSON, OF CHICAGO, ILLINOIS, ASSIGNEES TO UNION SPECIAL MACHINE COMPANY, OF CHICAGO, ILLINOIS, A CORPORATION OF ILLINOIS.

SEWING MACHINE.

Application filed May 19, 1924. Serial No. 714,300.

To all whom it may concern:

Be it known that we, WILLIAM B. LONG and NATHAN E. HANSON, citizens of the United States, residing at Chicago, in the county of Cook, State of Illinois, have invented certain new and useful Improvements in Sewing Machines, of which the following is a description, reference being had to the accompanying drawing and to the figures of reference marked thereon.

The invention relates to new and useful improvements in sewing machines and more particularly to a two-needle overedge sewing machine.

In a machine of the above type, the overedge stitch is made by means of two thread carrying needles, one of which passes through the material and the other over the edge of the material. A single threaded looper operates with both needles beneath the work support and secures the needle thread loops. Associated with the needles above the work support is a swinging finger which moves into engagement with the needle thread of the inner needle, or needle which penetrates the fabric and moves said thread toward the front of the machine where it can be engaged by a hook, and the hook carries the needle thread laterally to a position where it may be entered by the other needle, that is, the needle which goes over the edge. Such a machine is shown and described in the patent granted February 19, 1918 to Robert R. Hughes, Jr., No. 1,257,239.

An object of the present invention is to provide a rigid bracket structure which is capable of supporting both the oscillating finger and the oscillating hook, which bracket structure is adapted to be attached to an ordinary two-needle sewing head, and which bracket structure operates to insure the proper co-ordination and alinement of these members.

A further object of the invention is to provide devices for connecting the oscillating hook with the shaft beneath the work support at a point adjacent the stitching point, so that said operating devices will consist of few and short parts and be free from excessive vibration when the machine is driven at a high speed.

These and other objects will in part be

obvious and will in part be hereinafter more fully disclosed.

In the drawings which show by way of illustration one embodiment of the invention—

Figure 1 is a front view of a machine embodying our improvements, the work support being omitted for the sake of clearness;

Fig. 2 is a horizontal sectional view of the machine taken immediately beneath the work support;

Fig. 3 is a sectional view on the line 3—3 of Fig. 2;

Fig. 4 is a detail showing the needles, the thread finger and thread hook with the thread finger at the rear end of its stroke, and the thread hook at the lefthand end of its stroke;

Fig. 5 is a similar view but showing the finger as having moved across the path of the needle carrying the thread of the left-hand needle toward the front of the machine, and the hook as having been retracted to engage this thread;

Fig. 6 shows the hook moved back sufficiently so as to position the loop of the left-hand needle thread carried thereby for the righthand needle to enter between the strands thereof, and

Fig. 7 is a plan view of the lever for carrying the thread hook.

The machine to which our invention is applied consists of a bed plate 1 having a standard 2 carrying an overhanging arm 3 on which a needle bar 4 reciprocates. Said needle bar is reciprocated by means of a needle lever 5 which is connected to the needle bar by a link 6. The needle lever is oscillated by an eccentric strap 7 which operates with an eccentric 8 on the main shaft 9. This main shaft 9 is journaled in the lower part of the standard 2 and in the bracket 10 at the front end of the machine.

The bracket 10 serves as one of the supports for a cloth plate. This needle bar is provided with two needles 11 and 12. Cooperating with the needles 11 and 12 beneath the work support is a thread carrying looper 13. Said thread carrying looper is given an oscillation into and out of the needle thread loops and is also moved laterally so as to avoid the needles. The lateral movement of

the looper is secured through a yoke 14 which cooperates with an eccentric on the main shaft 9. The oscillations of the looper are derived from a reciprocating rod 15 which is connected to the looper by means of a forked arm 16 and pivoted block 17. The rod 15 is reciprocated by means of a lever 18 which is connected by means of a link 19 to an arm 20 pivoted at 21. Said arm 20 is oscillated by means of a link 22 which is connected to the needle lever extension 23. Certain of the levers, links and arms just referred to are so arranged as to move into alinement and across dead center so that the looper is given an extended dwell at the forward end of its stroke. This arrangement broadly of links and levers is shown, described and claimed in our co-pending application Serial No. 714,299, filed of even date herewith. The specific construction of links, levers and arms for accomplishing this purpose, form no part of our invention, but are shown, described and claimed in an application filed by Roy W. Redin, Serial No. 715,416, of even date herewith.

The present invention as has been suggested above has to do entirely with the stitch forming elements above the work support. Associated with the needles is a finger 24 which is adapted to move across the path of the lefthand needle and carry the lefthand needle thread toward the front of the machine. Associated with this finger is a thread hook 25 which moves in a direction substantially at right angles to the direction of feed, and this hook engages a thread of the lefthand needle moved toward the front of the machine by the finger 24 and carries it laterally into position for the righthand needle to enter the same.

The thread finger 24 is carried by a lever 26 (see Figures 1 and 3). The lever 26 is mounted on a fulcrum pin 27 passing through the ears 28 and 29 of a bracket member 30. The work is held on the cloth plate by means of a presser foot 31. This presser foot is carried by a presser bar 32. The bracket 30 is mounted on the presser bar. Said presser bar extends through a bearing bracket 33 and a bearing bracket 34. A guide bar 35 slides vertically in the lugs 36 and 37. This guide bar and the presser bar are connected by means of an arm 38 so that they move up and down together. The purpose of the guide bar is to prevent the presser bar from rotating in its bearings. At the upper end of the bracket 30 there is a projecting split lug 39 through which the presser bar extends, and said lug is clamped tightly to the bar by means of a screw 40. The bracket 30 depends below the bearing bracket 34 and the lug 37. The presser bar has a flat side 32^a so that when the split bearing 39 is set

up against the presser bar it will be held 65 rigidly from oscillating on said bar.

The upper end of the lever 26 is connected to a link 41 at 42. The other end of the link 41 is connected to a ball stud 43 mounted on the end of an arm 44 which is formed as a 70 part of a sleeve 45 carried by the needle bar and secured thereto by set screws 46, 46. When the ball stud is at the lower end of its reciprocation, the link 41 is nearest to a horizontal position. As this ball stud moves upwardly, then the link will be inclined. As the link is inclined, it will pull in on the upper end of the lever 26 and cause the finger 24 to move outwardly across the path of the lefthand needle as has been referred to above. This particular link operating mechanism for the finger is shown in the patent to Hughes above referred to. Inasmuch as the bracket is mounted on the presser bar, when the presser bar is lifted, the lever 26 will also be lifted, so that the thread finger maintains a predetermined position relative to the presser foot.

The thread hook 25 is carried by the lever 47. The inner end of this lever 47 extends 90 between the perforated lugs 48 and 49 formed in the lower part of the bracket 30 and is pivotally mounted therein by means of a pivot pin 50 which is clamped to the lever. The lever is oscillated on the bracket 30 by means of a link 51 which is pivoted at its inner end to a ball stud 52 carried by the arm 53 of the lever 47. The rear end of the link 51 is pivotally connected to a ball stud 54 which is fixed to the upper end of a lever 55. The lever 55 is mounted on a short shaft 56 carried by a bracket 57 secured by means of screws 58, 58 to the bed plate of the machine. Said lever 55 intermediate its ends carries a projecting ball stud 59 to which an eccentric strap 60 is connected. Said eccentric strap 60 cooperates with an eccentric 61 on the main shaft 9. It will thus be seen that as the main shaft 9 rotates, the lever 55 will be oscillated back and forth, and through the link 51 will swing the lever 47 carrying the thread hook 25. Thus it is that we are able to get a very direct drive for the thread hook from the main shaft beneath the work support and at a point close to the forward end of the shaft, so that the parts for operating the thread hook are comparatively short and comparatively few and are positive in their actions, whereby the machine may be driven at high speed, with little or no undesirable vibration in the parts. The material is moved across the work support by means of a feed dog 62 carried by a feed bar 63 of the usual construction. The presser bar may be readily raised and lowered carrying with it the lever supporting the thread hook, so that the thread hook always oscillates in a definite

position relative to the presser foot. The link 51 is pivotally connected to the lever 55 by the ball stud 54. This ball stud is so located that the link 51 may turn thereon 5 when the presser bar is raised and lowered.

It is obvious that minor changes in the details of construction and arrangement of the parts may be made without departing from the spirit of the invention as set forth 10 in the appended claims.

Having thus described the invention, what we claim as new and desire to secure by Letters-Patent, is—

1. A sewing machine including a bed 15 plate, a work support, a presser foot for holding the material on the work support, a presser bar carrying said presser foot, a pair of needles, a thread carrying looper cooperating with said needles beneath the 20 work support, a thread finger movable across the path of one of said needles for deflecting the thread thereof in front of said needle, a thread hook for engaging said deflect- 25 ed thread and forming a loop therein for the other needle to enter, a lever supporting and operating said finger, a lever supporting and operating said hook, and a single unitary bracket having a lug on which one of said levers is mounted and having an independent 30 lug on which the other lever is mounted, said bracket being carried by the presser bar and movable up and down therewith.

2. A sewing machine including a bed 35 plate, a work support, a presser foot for holding the material on the work support, a presser bar carrying said presser foot, a pair of needles, a thread carrying looper cooperating with said needles beneath the work support, a thread finger movable 40 across the path of one of said needles for deflecting the thread thereof in front of said needle, a thread hook for engaging said deflect- 45 ed thread and forming a loop therein for the other needle to enter, a lever oscillating in a vertical plane and supporting and operating said finger, a lever oscillating in a horizontal plane and supporting and operating said hook, a single unitary bracket having a lug on which one of said levers is 50 mounted and an independent lug on which the other lever is mounted, said bracket being carried by the presser bar and movable up and down therewith, a needle bar, and means actuated by said needle bar for swing- 55 ing said lever carrying said finger.

3. A sewing machine including a bed 60 plate, a work support, a presser foot for holding the material on the work support, a presser bar carrying said presser foot, a pair of needles, a thread carrying looper 65 cooperating with said needles beneath the work support, a thread finger movable across the path of one of said needles for deflecting the thread thereof in front of said needle, a thread hook for engaging said deflect- 70

thread and forming a loop therein for the other needle to enter, a lever supporting and operating said finger, a lever supporting and operating said hook, a single unitary bracket on which said levers are mounted, 75 said bracket being carried by the presser bar and movable up and down therewith, said bracket having a pair of vertically arranged bearing lugs, and a short vertical shaft mounted in said bearing lugs on which 80 said lever carrying said hook is fixed and a separate lug on which said lever carrying the thread finger is mounted.

4. A sewing machine including a bed 85 plate, a work support, a presser foot for holding the material on the work support, a presser bar carrying said presser foot, a pair of needles, a thread carrying looper 90 cooperating with said needles, beneath the work support, a thread finger movable across the path of one of said needles for deflecting the thread thereof in front of said needle, a thread hook for engaging said deflect- 95 ed thread and forming a loop therein for the other needle to enter, a lever supporting and operating said finger, a lever supporting and operating said hook, a single unitary bracket on which said levers are mounted, said bracket being carried by the presser bar and movable up and down therewith, said bracket having a pair of vertically arranged bearing lugs, a short vertical shaft mounted in said bearing lugs on which 100 said lever carrying said hook is fixed, a pair of horizontally arranged lugs carried by said bracket, and a short shaft carried by said lugs on which the lever carrying the finger is mounted.

5. A sewing machine including a bed 105 plate, a work support, a presser foot for holding the material on the work support, a presser bar carrying said presser foot, a pair of needles, a thread carrying looper 110 cooperating with said needles beneath the work support, a thread finger movable across the path of one of said needles for deflecting the thread thereof in front of said needle, a thread hook for engaging said deflect- 115 ed thread and forming a loop therein for the other needle to enter, a lever supporting and operating said finger, a lever supporting and operating said hook, a single unitary bracket on which said levers are mounted, said bracket being carried by the presser bar and movable up and down therewith, said bracket having a pair of vertically arranged bearing lugs, a short vertical shaft mounted in said bearing lugs on which 120 said lever carrying said hook is fixed, a bracket beneath the work support, a lever mounted on said bracket, a link connecting the upper end of said lever to the lever carrying the hook for oscillating the hook, a main shaft beneath the work support, and an eccentric rod operated thereby and con- 125

nected to said lever for oscillating the hook. 6. A sewing machine including a bed plate, a work support, a main rotating shaft beneath the work support, an overhanging 5 arm, a needle bar mounted in said arm and carrying a plurality of needles, a thread finger above the work support for engaging the thread of one of said needles and deflecting it in front of the needles, a thread 10 hook adapted to engage said deflected thread and form a loop therein for the other needle to enter, a lever adapted to swing in a horizontal plane on which said hook is mounted, a bracket on said bed plate beneath the work

support and adjacent the stitching element, 15 a lever mounted on said bracket and projecting above the work support, a link for connecting the upper end of said lever to the lever carrying the thread hook, an eccentric on the main shaft, and an eccentric 20 rod operated thereby and connected to the lever projecting above the work support for oscillating the same.

In testimony whereof, we affix our signatures.

WILLIAM B. LONG.
NATHAN E. HANSON.
